[57] CLAIM

The ornamental design for a pharmaceutical tablet or similar article, as shown and described.

DESCRIPTION

FIG. 1 is a front perspective view of a pharmaceutical tablet or similar article showing my new design;

FIG. 2 is a top plan view thereof;

FIG. 3 is a front elevational view thereof;

FIG. 4 is a bottom plan view thereof;

FIG. 5 is a right side elevational view thereof, the left side elevational view being a mirror image of that shown;

FIG. 6 is a rear elevational view thereof.
